UNITED STATES PATENT OFFICE.

ERWIN B. LOEWENBACH, OF MILWAUKEE, WISCONSIN.

SHOE.

992,221.

Specification of Letters Patent. Patented May 16, 1911.

Application filed November 20, 1909. Serial No. 529,014.

To all whom it may concern:

Be it known that I, ERWIN B. LOEWENBACH, a citizen of the United States, residing at Milwaukee, county of Milwaukee, 5 and State of Wisconsin, have invented new and useful Improvements in Shoes, of which the following is a specification.

My invention relates to improvements in shoes, with especial reference to that class 10 of shoes used in gymnasiums or for playing games, such as tennis, where a light shoe which will not mar a floor or dig up the earth is desired.

The object of my invention is to provide a 15 more durable and less expensive shoe than those heretofore used. Also to provide such a shoe with a suitable spring heel without adding materially to the expense of manufacture.

20 In the following description, reference is had to the accompanying drawings, in which—

Figure 1 is a side view of a shoe embodying my invention. Fig. 2 is a plan view of 25 the same. Fig. 3 is a perspective view showing the sole and spring heel, the several members thereof being partially separated, the upper leather being partially broken away and the remainder turned to the position which it occupies when attached to the sole. Fig. 4 is a sectional view, drawn on line $x-x$ of Fig. 1. Fig. 5 is a view similar to Fig. 4, showing a modified form of construction. Fig. 6 is a sectional view, drawn 30 on line $y-y$ of Fig. 5.

Like parts are identified by the same reference characters throughout the several views.

The sole of my improved shoe includes a 40 forming member A preferably of linoleum, cut to the contour of a shoe sole. This is placed upon a piece of soft flexible leather B similarly cut, but of larger size so that the piece B extends beyond the piece A on 45 all sides sufficiently to be turned up and inclose the margins of the piece A and preferably extend above its upper surface for a short distance. A heel piece C is interposed between the heel portions of the members A 50 and B with its front margin skived or beveled at D to avoid an abrupt shoulder in the rear of the instep which would otherwise prevent conformity of the piece B along the entire under surface of the pieces A and C. 55 This piece C preferably comprises a cake of ground cork, the particles of which are

united by rubber or other suitable cement. A piece of canvas E covers the piece A and is of substantially the same size as the piece B. This forms the inner lining of the sole 60 in the completed shoe. The members A, B, C and E are then glued together to form the sole. The upper F, preferably of leather, is then applied in a reversed position, to the under marginal surface of the member B 65 and secured thereto and to the canvas member E by stitching at G, after which the upper is turned to the position of use, in which position it holds the margins of the members B and E in an upright or raised position, 70 covering the margins of the linoleum member A, as clearly shown in Fig. 4. The linoleum member A is the forming member, this alone having the required rigidity.

In Figs. 5 and 6, I have illustrated a heel 75 portion provided with a counter. In this case, the counter is applied while soft and while the upper is in position for sewing, after which the shoe is turned and the leather forming the counter is stiffened by 80 wetting and drying it.

So far as I am aware, the forming sole members whereby these shoes may be made in rights and lefts, together with heel lifts and counters, are novel features in a turned 85 shoe, but by their use, I am enabled to provide tennis and gymnasium shoes with substantially the same contours as in the case of shoes formed on a last.

Having thus described my invention, what 90 I claim as new, and desire to secure by Letters Patent, is—

1. In a shoe, the combination of a sole having a flexible and substantially inelastic forming member of sufficient thickness and 95 rigidity to give shape to the sole, a covering of soft leather for the under surface of the forming member, extended upwardly over the margins of the forming member, an upper stitched to the under surface of said covering at its margins and doubled upon itself into a position to hold said margins in a raised position, and a heel counter having its lower margin doubled upon itself between the body of the upper and the upturned edge of the upper, and stitched to such upturned edge and to the margin of the soft leather sole covering; said forming member and sole covering being secured together, and said forming member not being 11 directly connected with the upper.

2. In a shoe the combination of a flexible

forming member, a compressible resilient heel member applied under the heel portion of the forming member, a flexible lower covering of soft leather, an upper covering of 5 canvas, and a shoe upper stitched to the under surface of the leather covering and doubled upon itself into a position to hold the margins of the coverings in a raised position and retain the forming and heel 0 members in position.

3. In a shoe, the combination of a sole having a linoleum forming member inclosed by a lower covering of soft leather and an upper covering of canvas both projected beyond the forming member, and an upper 5

stitched to the under surface of the lower covering and doubled upon itself into a position to hold the projected margins of the covering in a raised position, together with a cushion heel piece of cemented cork fragments, interposed between the heel portion of the forming member and the leather covering and held in position thereby. 20

In testimony whereof I affix my signature in the presence of two witnesses.

ERWIN B. LOEWENBACH.
